UNITED STATES PATENT OFFICE

2,290,899

MAGNETIC SOUND RECORDING DEVICE

Arnold Staepfleldt, Berlin, Germany, assignor to
 C. Lorenz Aktiengesellschaft, Berlin-Tempel-
 hof, Germany, a company

Application August 4, 1939, Serial No. 288,333
 In Germany August 4, 1938

5 Claims. (Cl. 192—143)

Magnetic recording devices of the type designated as steeltone machines are known which comprise a mechanism coupled with the motor drive and having a hand or pointer for indicating the length of that part of the wire- or tape-shaped record carrier which at the time is available for recording. Also switching means have been provided which act to stop the machine after a predetermined part of the record carrier has been uncoiled. In most of the latter cases 10 indicating device of the type having rotary pointers are employed. Furthermore marker plates have been used which have a nut screw in engagement with a spindle or lead screw and arranged to move along this spindle under the influence of a guide rod for such nut. This rod is mounted on a casing in which the well-known bobbins or reels are contained, and is displaceable in its longitudinal direction. When now the nut comes against an adjusting ring the guide rod is displaced and thereby acts to stop the machine. Such an arrangement is shown, for example, in my copending application Ser. No. 277,780 filed June 9, 1939. This arrangement has the disadvantage that the machine will be stopped by every impact influencing it and will be stopped also whenever the guide rod is touched.

The invention has for its object to overcome these drawbacks. In a preferred embodiment of the invention the said nut screw is guided in a slot of the casing and is arranged to actuate two flaps by the intermediary of levers which are adjustable along the casing. These flaps act to operate electric contacts which may control means to open the motor circuit or operate a declutching means in any well known manner and thereby to stop the machine.

An embodiment of this kind is described hereafter, by way of example, reference being had to the accompanying drawing in which

Fig. 1 is a fragmentary sectional view thereof while Fig. 2 shows a section on line 2—2 of Fig. 1. 1 denotes a casing in which the well-known reels, not represented in the drawing, are located. A lead screw or spindle 2 is revolvably mounted in the casing 1 and is connected with a motor drive A which comprises two bevel gears, as shown. Spindle 2 is in engagement with a nut screw 3 guided in a slot b of the casing 1. Nut 3 carries a pointer 14 that belongs to a scale 15 which extends longitudinally of the casing. The nut 3 also has two stops 4, 5 rigidly fitted to it. Two adjustable slides 6, 7 are guided in a longitudinal slot c of casing 1 and have each a lever 55

8, 9 fulcrumed to them. These levers are arranged to be deflected by the stops 4, 5, respectively. One of the levers 8, 9 serves to stop the machine upon its forward limit of operation, while the other lever is to limit the recoiling length. The levers 8, 9 to such end act on two flaps 10, 11, mounted in the casing 1 by means of a trunnion d common to them. The flaps 10, 11 have each an arm 13 and 12, respectively. These arms are arranged to close contacts e, f and thereby to stop the machine in any well known manner, for example, by stopping the motor or opening a driving clutch. Such stoppage will thus occur whenever either flap 10 or flap 11 is turned by lever 9 or 8, respectively, these levers being actuated by the stops 4, 5, as before described. Slide 6 may be displaced in slot c to limit the operating time of the machine to a desired time of talking. Equally, slide 7 allows of 20 limiting the recoiling period in accordance with each speech. For instance, in case it is desired to repeat a recorded speech, slide 7 may be so adjusted that the machine shall only recoil until the commencement of the desired speech. Much time will thus be saved, since it is not necessary to recoil the whole record carrier.

Another advantage is that the machine will not be affected by shocks and will not be stopped accidentally.

30 To provide for a remote indication of the successive positions of the record carrier a potentiometer may be arranged parallel to spindle 2 and the nut 3 may be equipped with a contact member for such potentiometer. The various 35 positions this contact member assumes when traveling along the potentiometer, and which accord with the successive positions of pointer 14 and equally accord with the record-carrying portion of the recording wire or tape, may then be 40 transmitted in known manner to a remote place.

What is claimed is:

1. A sound recording machine which comprises a drive means, a rectilinear scale, adjustable 45 slides adapted to be displaced in both directions of this scale, levers fulcrumed to these slides, movable stops to deflect these levers, means controlled by said drive means for moving said stops along said scale and into operative position with respect to said levers, flaps arranged to move under the control of deflection of said levers, and electric contacts to effect the stoppage of the machine, such contacts being under the control of movement said flaps.

2. A sound recording machine according to

claim 1, which has a casing provided with a slot for guiding said adjustable slides.

3. A sound recording machine according to claim 1, wherein said controlled means includes a lead screw controlled by said drive means, and a nut screw in engagement with this lead screw and fitted with the said stops, further comprising a casing provided with a slot for guiding this nut screw, and a pointer for the said scale, this pointer fastened to the said nut screw.

4. A sound recording machine according to claim 1, in which the said flaps are mounted in the casing by means of a trunnion common to them.

5. A sound recording machine according to claim 1, having arms rigid with said flaps to operate the said contacts.
